UNITED STATES PATENT OFFICE.

CHARLES F. BUENTE, OF PITTSBURGH, PENNSYLVANIA.

CONCRETE-PIPE MACHINE.

Application filed August 6, 1921. Serial No. 490,292.

To all whom it may concern:

Be it known that I, CHARLES F. BUENTE, a citizen of the United States, residing at Pittsburgh, in the county of Allegheny and 5 State of Pennsylvania, have invented a new and useful Improvement in Concrete-Pipe Machines, of which the following is a full, clear, and exact description.

My invention relates to concrete pipe machines.

An object of my invention is such a machine of simplified construction wherein the parts are accessible for repair and adjustment.

15 A further object of my invention is such a machine wherein a plurality of tampers are used with means provided for rendering certain of said tampers ineffective at certain stages of the operation of the machine.

A further object of my invention is such a machine wherein the tamping effect is uniformly produced with such machine in the manufacture of pipes of varying diameter and thickness of shell.

25 A further object of my invention is such a machine wherein the force for operating the tamping means is applied substantially in line with the tamping force so as to eliminate side strains in any direction.

30 A further object of my invention is such an arrangement wherein the tamping box is guided as distinguished from guiding the tampers themselves.

35 A further object of my invention is such a machine wherein the friction box for holding the tampers is centralized laterally and transversely with respect to the operating means, so as to completely avoid vibration of the tampers.

40 A further object of my invention is such a machine wherein the core shaft operating means is provided with anti-friction devices so as to reduce the friction encountered in the operation of the core shaft.

45 A further object of my invention is such a device wherein the core shaft is provided with means for increasing the area of contact between the shaft and the guide.

50 A further object of my invention is such a device wherein the core is rotated in the same direction as the mold, but at a slower speed.

A further object of my invention is such a device wherein a split gear is used for op-

erating the device so that gears of different 55 diameters may be easily applied with the result that a definite lineal movement is given to the concrete for each blow of the tamping devices.

A further object of my invention is such 60 a device wherein the operating speed for the mold and core is so proportioned with respect to the feeding device as to get a uniform tamping effect throughout the area of pipes of different diameters and shell thick- 65 ness.

A further object of my invention is such a machine wherein a bell cap is provided having portions permitting tampers to pass therethrough during the formation of the 70 shell; a further portion to act as a core during the formation of the bell of the pipe and a further portion having the incidental effect of rendering some of the tampers ineffective during the formation of the bell. 75

Further objects will be apparent to those skilled in the art upon reading the following description taken in connection with the accompanying drawings, and in which:

Figure 1 is a front elevation of a machine 80 embodying my invention and showing one of the molds in section;

Figure 2 is an end elevation of the machine shown in Figure 1;

Figure 3 is a partial section and side elevation showing the tampers and the operating means therefor on an enlarged scale; 85

Figure 4 is a sectional elevation of the feeding device;

Fig. 5 is a section on line V—V of Figure 3; 90

Figure 6 is a view similar to Figure 5 wherein the bell cap has been rotated 90°;

Figure 7 is a plan view of the core shaft and means for operating the same;

Figure 8 is a section on line VIII—VIII 95 of Figure 7;

Figure 9 is an elevation of the tamper box and means for operating the same.

Referring to the drawings, Figure 1 shows a device comprising a turn table 1 on which 100 are placed two molds 2 and 3. The molds are mounted on mold bases 4 which are provided underneath with gear teeth meshing with the pinion 5 and by which the said molds are rotated. The molds rotate around a center pin 6. The turn table 1 is held in place by a pin 7 entering a suitable opening for the center pin 6 and operated by a 105

handle 8. The turn table 1 is mounted on balls 9 and mold bases 4 are similarly mounted on balls 10 for the purpose of rendering the same easily rotated. The gear 5 is mounted on a shaft 11 which is provided with a split gear 12, meshing with the pinion 13. The gear 13 is mounted on a driving shaft 14 which drives a pulley on the shaft 16 through the belt 15 for operating the 10 tamping means to be later described.

Mounted on the shaft 14 is a sprocket 17. A chain 18 passes over the sprocket 17 and also over a sprocket 19, as shown in Figures 2 and 4. The sprocket 19 is mounted on a 15 shaft 20, carrying a gear 20^a meshing with a gear 20^b on the shaft 20^c. The shaft 20^c carries blades 21 in a trough 22 for feeding the mixed concrete into the mold. The shaft 20 is provided at the end of the trough 22 with a rotary cutter 21^a which delivers a 20 ribbon of concrete of uniform area into the trough 80, which is provided with a screw conveyor 81 operated from the shaft 20^c through sprockets and chain 82.

25 When it is desired to feed concrete into a mold of smaller diameter than that shown in Figure 2, the gears 20^a and 20^b are removed from their respective shafts and gears 83 and 84, both illustrated in dotted lines in 30 Figure 2, are substituted, whereupon the screw conveyor and the shaft 20^c and the other members of the feeding mechanism are moved to the left to the dotted line position shown in Figure 2. The concrete is placed 35 in the hopper 23 and the entire feeding device is carried by channels 23^a, as shown in detail in Figure 4.

The driving shaft 14 is also provided with 40 a clutch 25 for operatively connecting the sprocket 17 to the shaft 14, that is to say, when the clutch is closed the sprocket 17 rotates with the shaft 14 and when the clutch is open the sprocket does not rotate with the shaft 14. The shaft 14 is driven from any 45 suitable source of power connected with the gear 26 which is connected to the shaft 14 through a clutch 27. The shaft 14 carries a clutch 28, one side of which clutch is connected with a gear 29 loosely mounted on 50 the shaft 14. The gear 29 meshes with a gear 30 loosely mounted on the shaft 11 but rigidly connected to a smaller gear 31. The gear 31 meshes with a larger gear 32 loosely mounted on the shaft 14 but rigidly connected 55 to a drum 33 also loosely mounted on the shaft 14 and around which a cable 34 is wound for a purpose to be later described.

Rigidly mounted to the shaft 11 is a 60 sprocket 35 over which passes a chain 36 for connecting the shaft 11 with the shaft 37. Mounted on the shaft 37 is a bevel gear 38 meshing with a larger bevel gear 39 slidably connected with the core shaft 40.

65 Mounted inside the mold 3 is a core 41 connected with the core shaft 40 and mount-

ed on balls 42. The core 41 is rotated in the same direction as the mold 3 but at a slower speed. The regulation of this rotation is effected through the sprocket 35, chain 36, shaft 37 and gears 38, 39 and shaft 40.

70 The core 41 has attached thereto cables 43, best shown in Figures 1 and 7. The cables 43 pass over sheaves 44 and 45. The sheaves 44 are connected to the frame 46 and the sheaves 45 to a movable cross-head 75 47 also carrying a sheave 48. A sheave 49 is mounted on the frame 46 and a sheave 50 is also carried by said frame. The cable 34 passes from the drum 33, as shown in Figure 1, over the sheave 49 and from there 80 around the sheave 48 and then around the sheave 50 and is attached to the movable cross-head 47 at 51. The ends of the cables 43 are attached to the frame 46 at 52. When it is desired to raise the core 41 from the 85 mold, the drum 33 is rotated and the cable 34 moves the cross-head 47 to the left, as shown in Figure 7, thus raising the core through the cables 43.

90 The friction between the core and the concrete is very great and therefore a large force is necessary to raise the core out of the concrete. The core shaft 40 is mounted in a guide 53, shown in detail in Figure 8. The shaft 40 is provided with extensions 54, 95 one of said extensions being on and in line with each face of the shaft so as to increase the contact area of each face of said shaft with respect to the guide. Mounted in the guide 53 and in contact with the face of the core shaft (the face includes the shaft and the extension thereon) are a plurality of rollers 55 shown in plan view in Figure 7 and in sectional elevation in Figure 8. The arrangement of the core shaft with its extended faces and the anti-friction rollers in the guide greatly reduces the friction between the core shaft and the guide and thereby decreases the force necessary to raise the core, thus greatly adding to the ease and 100 satisfaction of operation of the device.

105 The tampers 56 are mounted in a friction box 57, each of the tampers 56 being uniformly supported with relation to the friction box by placing a spacing member 58 110 between the adjacent tampers. A spring 59 bears against the outside of one of the tampers and is put under compression by means of a cam 60 operated by a handle 61.

115 The tamping movement of the tampers is 120 imparted thereto by a train of gears shown in Figure 9. The gear 62 is mounted on the shaft 16, and meshes with a similar gear 63. The gear 62 meshes with the gear 64 and the gear 63 with the gear 65. The gears 64 and 125 65 are mounted on shafts 66 and 67 respectively, which carry fly wheels 68 and 69 respectively. Connected with the fly wheel 68 is a link 70 and connected with the fly wheel 69 is a link 71. The links 70 and 71 are 130

5 pivotally connected to the friction box 57, as shown in Figure 9. As shown in Figure 1 the link 70 (also link 71 not shown in Figure 1) are connected to the friction box 57 centrally of the tamping members and as shown in Figure 9 one of the links is connected to each side of the friction box so that the tamping power is applied to the tampers in line with the tamping force or the reaction force produced when the tampers strike the concrete. This arrangement is important as it completely eliminates vibration from the tamping means.

10 The friction box 57 is guided in its reciprocating movement by guide rods 72 and it will be noted that the tamping members themselves are not guided other than by the friction box.

15 The relation of the tampers to the concrete pipe is shown in Figure 3 during the formation of the body of the shell. As the pipe is built up the tampers are automatically pushed upward and when the pipe reaches the bell portion it is necessary to move the tampers to the left. This is accomplished by rotating the hand wheel 73 in the proper direction to cause the channel 74, which carries the tamping mechanism to be moved to the left, thus moving the tampers to the left also. The channel 74 is slidably mounted in the uprights 75 of the machine.

20 During the finishing operation and for a considerable distance prior thereto, it becomes necessary to eliminate or render ineffective one or two of the tampers because the pipe at its upper end becomes narrower than the body of the shell. In order to effect this a bell cap 76 is rotatably mounted on top of the core around the core shaft 40. During the formation of the body of the shell the bell cap 76 is in the position shown in Figure 5. That is to say the opening therein permits the tampers to pass therethrough into contact with the concrete. The cap is held in the position shown by a spring pressed pin 77 engaging a notch 77^a in a sleeve 78 held against rotation by an angle 78^a. When it is desired to form the bell of the pipe the pin 77 is pulled outwardly and the bell cap 76 is rotated in a clockwise direction to the position shown in Figure 6. This rotation brings a portion 76^a of the bell cap into position so that it acts as a core to support the interior portion of the concrete forming the bell of the pipe in the region of the tampers. As the beveled portion 79 comes under the tampers, one or more of the same thereafter engage the bell cap, and are not permitted to pass into contact with the concrete so that only one or two of the tampers are effective in tamping the concrete to form the bell. It will be noted that as shown in Figure 6 the tampers have been moved outwardly radially by operating the hand wheel 73, due to the increased diameter of the pipe at that

portion thereof. The portion 76^b of the bell cap is used as a "slicker" to smooth off the top of the pipe.

70 The operation of my machine is as follows:

With the gear 12 of a suitable size selected according to the diameter of the pipe to be made, the machine is started after one of the molds 3 has been moved into the position shown in Figure 1. The starting of the machine causes the rotation of the mold 3 through the gears 13, 12 and 5. The sprocket 17 is rotated upon the closing of the clutch 25. This in turn rotates the feeder 21 and causes the concrete to be fed into the mold.

75 The tampers are moved into the proper position by the proper operation of the hand wheel 73 and are operated by means of the belt 15 through the mechanism shown in Figure 9. The arrangement of the driving means for the mold and the tampers is such that each blow of the tamping means slightly overlaps each preceding blow thereof so as to produce a substantially equal tamping effect per unit area.

80 The core of the mold is rotated in the same direction as the mold by friction with the concrete, but is held to a lower speed through the sprocket 35, chain 36 and shaft 37 and the core shaft 40.

85 This operation is continued until the body of the shell is formed. When the bell is reached the tampers are moved outwardly radially by operating the hand wheel 73 in proper direction and when the flange or upper part of the bell is reached the pin 77 is pulled outwardly to allow the bell cap 76 to rotate from the position shown in Figure 5 to that shown in Figure 6 to place a core in the region of the tampers and also rendering 90 two (for illustration) of the tampers ineffective. When the bell is completed the clutch 25 is operated to disconnect the feeding mechanism and the mold and core are rotated a few times to allow the portion 76^b 95 to smooth off the top of the bell as it passes under that part of the bell cap.

100 In order to remove the core from the pipe the clutch 28 is closed, thus rotating the drum 33 and winding the cable 34 thereon. The winding of the cable 34 on the drum draws the cross-head 47 to the left as shown in Figure 7, thus raising the core and core shaft through the cables 43. This operation is carried out while the mold and core are 105 rotated so as to smooth the interior of the pipe and also this rotative movement decreases the power necessary to raise the core. After the core is removed, the turn table 1 is rotated and the mold 3 may be removed 110 from the table 1 to any desired point and from which the pipe section may be removed, and during the rotation of the table 1 the mold 2 is brought into position.

115 If it is desired to make a pipe of a diam-

eter different from that shown in the drawings, gears 12 and 13 of suitable size are substituted for those shown in the drawing, to so rotate the mold as to impart a lineal movement thereto of substantially the same speed as the arrangement shown in the drawings. Assuming that a smaller pipe than that shown in the drawings is to be made, a larger set of gears 83 and 84 will be placed on the feeding device so that the rate of feed of concrete to the mold will be slower than with the arrangement shown in full lines in the drawings. The arrangement is such that the rate of rotation of the mold and the rate of feed to the mold are so coordinated with respect to the tamping means and the diameter and shell thickness of the pipe being made that a uniform tamping effect is produced per unit area of concrete entering into the construction of the pipe.

In making certain classes of pipe and in pipes of various classes in certain large diameters, it is frequently desirable to reinforce the shell. With my arrangement this may be done easily by placing the reinforcing means in position in the shell so that adjacent tampers may operate on the concrete at the sides of the reinforcing means.

If it is desired to have some of the tamping means further apart than others so as to permit them to operate on adjacent sides of the reinforcing means, the spacing blocks 58 between the adjacent tampers may vary in thickness so as to permit of this operation.

My invention has many advantages which result from the construction shown and described, and whereby a plurality of tampers may be used, all of said tampers having uniform tamping effect; means are provided for eliminating some of the tampers when desired; pipe of varying thickness and of uniform density may be produced; the pipe may be reinforced to strengthen the same; the tamping box is guided as distinguished from guiding the tampers; the friction box for the tampers is centralized laterally and transversely, thus avoiding vibration of the tampers; means are provided for rendering the removal of the core much less difficult than heretofore; the lineal movement of the pipe shell is uniform for all sizes and the rate of feed varies inversely with the revolutions per minute of the mold, so as to produce uniform tamping effect per unit area of the concrete and a bell cap is provided which may remain in position during the entire operation of making the pipe, it being necessary to only rotate the bell cap during the formation of certain parts of the pipe.

Many other advantages will be apparent to those skilled in the art.

While I have shown and described in detail one embodiment of my invention, I desire it to be understood that I do not limit myself to the exact device shown and de-

scribed, as many changes may be made in the details without departing from the spirit of my invention.

I claim:

1. In a concrete pipe machine, the combination of a mold, a core therefor, means for rotating said mold, means for causing a relative rotative movement between said mold and core, means for maintaining a uniform feed of concrete into said mold in the formation of one size of pipe, and means whereby the rate of rotation of said mold may be varied and the rate of feed varied inversely to the rate of rotation of the mold in the formation of another size of pipe. 80

2. In a concrete pipe machine, the combination of a mold, a core therefor, means for feeding concrete into said mold, means for causing a relative rotative movement between said mold and core, and means whereby the rotation of the mold may be varied to provide substantially constant lineal speed to the periphery of molds of different diameters. 85

3. In a concrete pipe machine, a mold, a core therefor, and a composite tamper comprising a series of simultaneously and relatively individually movable coacting elements, substantially as described. 90

4. In a concrete pipe machine, the combination of a mold, a core therefor, and a composite tamper composed of a plurality of individually supported elements for operation in said mold. 95

5. In a concrete pipe machine, the combination of a mold, a core therefor, and a composite tamper composed of a plurality of spaced individual elements supported by friction for operating at varying points in said mold. 100

6. In a concrete pipe machine, the combination of a mold, a core therefor, a composite tamper, and means for rendering some of the tamping elements ineffective. 105

7. In a concrete pipe machine, the combination of a mold, a core therefor, a tamper composed of a plurality of individually supported co-acting elements for operation in said mold, and means for rendering some of said elements ineffective. 110

8. In a concrete pipe machine, the combination of a mold, a core therefor, a tamper composed of a plurality of spaced individual elements supported by friction for operating at varying adjacent points in said mold, and means for rendering some of said elements ineffective. 120

9. In a concrete pipe machine, the combination of a mold, a bell cap for said mold, a core for said mold, a composite tamper comprising a plurality of elements, and means on the bell cap for rendering some of said elements ineffective. 125

10. In a concrete pipe machine, the combination of a mold, a core therefor, tamping 130

means, a holder for said tamping means, and means for applying operative power to said holder substantially along the line of the tamping force.

6 11. In a concrete pipe machine, the combination of a mold, a core therefor, tamping means, a holder for said tamping means, means for applying operative power to said holder substantially along the line of the 10 tamping force, and guiding means for said holder.

12. In a concrete pipe machine, a mold, a core therefor, a shaft connected to the core and rotated by friction between the core and 15 the concrete being molded, a guide for said shaft having anti-friction means between the shaft and the guide, and means for controlling the rotation of said shaft while raising the core out of the concrete in the mold, 20 substantially as described.

13. In a concrete pipe machine, the combination of a mold, a core therefor, a polygonal shaft connected to the core, a guide for said shaft having anti-friction means between the shaft and the guide, and means for controlling the rotation of said shaft while raising the core out of concrete in said mold.

14. In a concrete pipe machine, the combination of a mold, a core therefor, a square shaft connected to the core, a guide for the shaft, anti-friction means between said guide and shaft, and means for controlling the relative rotation between the core and concrete in the mold and raising the core.

35 15. In a concrete pipe machine, a mold, a core therefor, a shaft connected to the core, a plurality of oppositely extending projections on said shaft, a guide for said shaft, and anti-friction means between said guide and said projections, substantially as described.

16. In a concrete pipe machine, a mold, a core therefor, a polygonal shaft connected to the core, a plurality of oppositely extending projections on said shaft, a guide for said shaft, and anti-friction means between said guide and said projections, substantially as described.

45 17. In a concrete pipe machine, a mold, a core therefor, a square shaft connected to the core, a plurality of oppositely extending projections on said shaft, a guide for said shaft, and anti-friction means between said

guide and said projections, substantially as described.

55 18. In a concrete pipe machine, the combination of a rotatable mold, a core therefor, tamping means therefor, and a bell cap provided with a portion for acting as a core during the formation of the bell of the pipe.

60 19. In a concrete pipe machine, the combination of a mold, a core therefor, tamping means for operation between said mold and core, and a bell cap having a portion for acting as a core during the formation of a bell 65 and another portion acting to smooth and finish the end of the pipe.

70 20. In a concrete pipe machine, the combination of a mold, a core therefor, tamping means for operating between said mold and core, and a bell cap permitting said tamping means to operate therethrough and having a portion acting as a core during the formation of the bell of the pipe and a portion for smoothing and finishing the end of 75 the pipe.

21. In a concrete pipe machine of the type wherein there is a mold and a core for forming the shell of the pipe and tampers for tamping the concrete, the combination of a 80 bell cap provided with means acting as a core for formation of the bell and for finishing and smoothing the end of the pipe.

85 22. In a concrete pipe machine of the type wherein there is a mold and a core for forming the shell of the pipe and tampers for tamping the concrete, the combination of a rotatable bell cap permitting the passage therethrough of the tamping means in one position of the bell cap and acting as a core 90 in the region of the tamping during the formation of the bell.

95 23. In a concrete pipe machine of the type wherein there is a mold and a core for forming the shell of the pipe and tampers for tamping the concrete, the combination of a rotatable bell cap permitting the passage therethrough of the tamping means in one position of the bell cap and acting as a core 100 in the region of the tamping during the formation of the bell, and means for holding said bell cap in said first position.

In testimony whereof, I have hereunto set my hand.

CHARLES F. BUENTE.
